UNITED STATES PATENT OFFICE.

PASQUALE RODOCCIA, OF PROVIDENCE, RHODE ISLAND.

STREET INDICATING AND ADVERTISING DEVICE FOR MOTOR VEHICLES.

Application filed September 24, 1921. Serial No. 502,987.

To all whom it may concern:

Be it known that I, PASQUALE RODOCCIA, a citizen of the United States, residing at Providence, in the county of Providence and 5 State of Rhode Island, have invented certain new and useful Improvements in a Street Indicating and Advertising Device for Motor Vehicles, of which the following is a specification.

10 This invention relates to a street indicator for trolley cars or other vehicles; and has for its object to provide a simple and effective mechanism in which a ribbon of suitable material is mounted to be wound 15 from one roll to another, and having indicated upon its face in spaced apart relation the names of the different streets of the route travelled, and to provide a motor which is energized by contact with members located upon the trolley wire to operate the ribbon rolls and bring into view the name 20 of the next street which the car is approaching.

A further object of the invention is to 25 provide an electrically operated motor connected to each roll for operating them independently of each other, to wind the ribbon alternately on these rolls by a step by step action.

30 A still further object of the invention is to provide means whereby the motor may be manually operated when desired, independent of the power received through the trolley.

35 With these and other objects in view, the invention consists of certain novel features of construction, as will be more fully described, and particularly pointed out in the appended claims.

40 In the accompanying drawings:

Figure 1 is a side elevation showing a portion of a street car in section with my improved street indicator device mounted in the center thereof suspended from the ceiling.

Figure 2 is an enlarged view of the device showing the roll casing broken away to illustrate the operating mechanism within.

Figure 3 is a side elevation of reduced 50 size illustrating the casing as provided with a plurality of openings through which three or more lines of reading matter may be ob-

served; also showing spaces at either end of the casing upon which advertising matter may be displayed.

55 Figure 4 is a sectional view on line 4—4 of Figure 2.

Figure 5 is a side elevation showing a detail of the motor in the form of a solenoid connected by a flexible tape to an operating drum, and a pawl and ratchet mechanism by which the drum is connected to the driving jack-shaft.

60 Figure 6 also shows the motor and the drum, and in addition shows the coil-spring connected to the drum for rewinding the tape thereon when the motor has been de-energized, after an operating stroke.

65 Figure 7 is a detail illustrating means for ringing a bell each time the motor is energized, to call the attention of the passengers to the name of the street being approached.

70 Figure 8 is a detail showing the trolley as having two side arms and a bracket located upon the trolley-wire extending to one side thereof in position to be engaged by one of the trolley-arms upon passing; also showing an independent circuit adapted to be closed by the car conductor by energizing each of the motors independent of each 75 other and also independent of the trolley circuit.

75 With reference to the drawings, 10 designates the trolley-wire on which is supported contact members 11 at intervals along the same, each contact being preferably provided with a flexible wiping member 12, and these contacts are usually placed midway between the cross streets of the route upon which the car is travelling, or they may be 80 placed at any other desired points along the trolley-wire. On the usual trolley-pole 13 I have mounted oppositely projecting contact arms 15 and 16, as best illustrated in Figure 8, so that each time the trolley passes 85 one of the brackets 11 in going in one direction, a contact is made through the arm 15 to conduct the current from the trolley-wire through wire 17 to the motor 18 to energize the apparatus presently described in one 90 direction, and when the car is going in the opposite direction the trolley-pole is swung about and the arm 16 engages the contact 95 12, conducting the current through the wire

100

19, to energize the motor 20 and so operate the indicating mechanism in the opposite direction.

In the construction of my improved indicating mechanism, I provide an upper roll 21, and a lower roll 22, between which the ribbon or strip 23, of cloth or other suitable material extends to be wound from one roll onto the other as they are alternately actuated by their respective motors. This ribbon is preferably designed to carry the names of the different streets on the different routes at spaced apart intervals along its length, but any advertising or other matter may also be carried thereby. These rolls are mounted to be rotated between two vertically disposed frame members 40, the lower roll having a spring-pressed center 24 at one end and to its shaft 25 at its opposite end is connected a ratchet toothed clutch member 26 which is engaged by a corresponding clutch member 27, on the end of the jack-shaft 28.

This clutch member 27 is provided with an annular groove engaged by one end of the lever 61, pivoted at 62, the opposite end of which lever is connected to lever 63, the free end of the latter extending into the path of pin 64, in solenoid core 39. It will, therefore, be seen that when the core 39 is at the end of its outward movement, the pin 64 will engage the lever 63 and in turn move the lever 61 to withdraw the clutch member 27 from the clutch member 26, thus freeing the rollers so that they may be operated in an opposite direction by the other driving mechanism, if necessary, and also to free the rollers from any vibration or movement of the operating parts, in order that the rollers may remain in their adjusted positions.

The inward movement of said core on its operating stroke releases the clutch member 27 to move under influence of its spring 29 into engagement with its clutch member 26 to drive its roll.

On this jack-shaft is mounted a ratchet gear 30, which is engaged by a pawl 31 providing a detent to prevent a backward rotation of this jack-shaft when the roll is rotated in a reversed direction.

On this shaft is also mounted a large gear 32, engaging a small gear 33, the latter being provided with laterally extending pins 34, adapted to engage a spring pawl 35, to ring the bell 36 each time the rolls are rotated to bring into view the name of another street.

On this jack-shaft is also mounted a drum 37, about which is wound a flexible tape 38, the free end of said tape being connected to the core 39, of the solenoid magnet 18, which serves as a motor which, when energized, causes the drum to rotate on its shaft.

In order to connect this drum to this

shaft, to rotate the shaft in one direction only, I have keyed a ratchet gear 41 to the shaft and have mounted a spring-pressed pawl 42, see Figure 5, on the drum so that a forward rotating motion of the drum rotates the shaft through this pawl and ratchet.

In order that this drum may be rotated back to normal when released by the motor, I have provided a coil-spring 43, see Figure 75 6, one end of which is connected to the hub of the drum, while the opposite end is connected to the member 44, which is fixed to the roll-casing 45. By this construction of mechanism it will be seen that each time the motor is energized the roll is rotated, and that when the motor is de-energized the drum automatically rewinds the tape ready for another rotating operation upon its roll 22. The upper roll 21 is also provided with a spring-pressed center 46 at one end, and on its shaft 47 at the other end is mounted a ratchet clutch 48, which clutch is engaged by a corresponding spring-pressed clutch member 49 mounted on the jack-shaft 50. The balance of the operating mechanism mounted upon this jack-shaft 50 is an exact duplicate of that mounted upon the jack-shaft 28 of the roll 22, whereby the energizing of the solenoid 20 on this side of the casing operates the upper roll 21 to wind the street indicating ribbon from roll 22 back upon the roll 21 when the car is moving in the opposite direction.

In some instances it is desired to provide 100 guide-rolls 51, over which the ribbon 23 may be conducted for the purpose of carrying its displaying center portion back into substantial alignment with the axes of the rolls 21 and 22. All of these rolls and the operating 105 mechanism are preferably enclosed in a casing 45, having its two parts hinged together at their lower edge at 52, and provided with a snap or catch member 53 at their upper edges for retaining them in closed position.

The side walls of these casing members are each provided with an opening 54, through which the matter displayed on the ribbon 23 may be observed from either side of this casing, so that a single casing may be 115 provided and supported in the middle of the car, as illustrated in Figure 1, and the matter on the ribbon may be observed through these openings 54 from either side thereof.

All about each of the openings 54 I have provided mirror flanges 55 for the purpose of reflecting the matter displayed upon the ribbon.

In some instances it is desired to provide 125 specially constructed advertising display surfaces 56 at the ends of the casing, as illustrated in Figure 3; also a plurality of openings 57 may be formed through each side wall of the casing so that a number of differ-

ent streets or other matter may be displayed through said openings.

In some instances it is desired to provide means whereby the conductor may operate 5 the rolls independent of the electrical operating motor. To accomplish this I have provided operating handles 58 on each of the jack-shafts on the outside of the casings. Then again in other instances it is 10 desired to provide electrical means independent of the trolley power whereby the different operating motors 18 and 20 may be energized by the car operator. To accomplish this in a simple and effective way, 15 I have provided an independent electric circuit, through which current from the batteries 59 will energize the motors 18 or 20 respectively when the switches 60 are closed.

It will be noticed that by the use of the 20 spring-pressed centers 24 and 46, that these may be readily pulled out to permit the removal of the rolls when a fresh ribbon is to be mounted to take the place of the old one. This is of advantage when a car is required 25 to run on different routes, which in practice is found to be often the case.

The foregoing description is directed solely toward the construction illustrated, but I desire it to be understood that I 30 serve the privilege of resorting to all the mechanical changes to which the device is susceptible, the invention being defined and limited only by the terms of the appended claims.

35 I claim:

1. In a street indicator of the character described, a ribbon carrying matter to be displayed, a roll upon which said ribbon may be wound, means for actuating said roll 40 including a drum, a flexible member wound about said drum, an electric motor connected to the free end of said flexible member to rotate the drum when the motor is energized, means for automatically disconnecting said 45 actuating means from said roll after each driving action, and means for rewinding said flexible member on said drum after each operation of said motor.

2. A street indicator of the character 50 described, a ribbon carrying matter to be displayed, a roll upon which said ribbon is to be wound, means for actuating said roll including a drum having operative connection with said roll, a pawl and ratchet mechanism 55 between said drum and said roll, whereby the latter may be operated in one direction by the movement of the drum, a flexible member wound about said drum, a motor connected with the free end of said flexible 60 member, whereby the drum is rotated when the motor is set in motion, and a spring for

rotating said drum in an opposite direction for rewinding said flexible member thereon after each effective operation of said motor.

3. In a street indicator as set forth in 65 claim 2, further characterized by said rewinding spring being placed under tension for rewinding the flexible member on the drum when said drum is rotated by the operation of said motor.

4. In a street indicator of the character described, a ribbon carrying matter to be displayed, a roll-shaft upon which said ribbon may be wound, a jack-shaft, a spring-pressed clutch connecting said shafts, a drum 75 connected to said jack-shaft through a pawl and ratchet mechanism, whereby the jack-shaft is rotated in one direction by said drum, a flexible member wound upon said drum, a motor connected to said member, 80 whereby the drum is operated to rotate said jack-shaft when the motor is set in motion and a spring for rewinding said flexible member on the drum after each effective operation of said motor.

5. A street indicator, as set forth in claim 4, further characterized by means for locking said jack-shaft against rotation except in one direction.

6. In a street indicator, of the kind described, a pair of spaced apart rolls each mounted on a shaft, a ribbon carrying matter to be displayed adapted to be wound alternatively upon said rolls by a step by step action, independent actuating means for each 90 roll-shaft, each of said actuating means comprising a jack-shaft, a spring-pressed clutch member connecting said jack-shaft with said roll-shaft, a drum freely mounted on the jack-shaft, a pawl and ratchet connection between said drum and jack-shaft, 100 whereby the latter is rotated in one direction by said drum, a flexible member wound about said drum, a motor connected to said member, whereby said drum is operated to 105 rotate said jack-shaft when the motor is set in motion, and a spring for rewinding said flexible member on the drum after each effective operation of the motor.

7. A street indicator, as set forth in claim 110 4, further characterized by means for automatically operating said clutch member to disconnect said shafts after each effective operation of the motor.

8. A street indicator, as set forth in claim 115 6, further characterized by means for automatically operating said clutch member to disconnect said shafts after each effective operation of the motor.

In testimony whereof I affix my signature. 120

PASQUALE RADOCCIA.
